UNITED STATES PATENT OFFICE.

CHARLES F. PRESLAR, OF NORWOOD, OHIO.

PUMP.

942,145.

Specification of Letters Patent.

Patented Dec. 7, 1909.

Application filed September 9, 1907. Serial No. 391,948.

To all whom it may concern:

Be it known that I, CHARLES F. PRESLAR, a citizen of the United States, residing at Norwood, in the county of Hamilton and State of Ohio, have invented new and useful Improvements in Pumps, of which the following is a specification.

This invention relates to a fluid actuating device for raising liquids from lower levels to higher ones or against pressure, the motor fluid being a gas, such as compressed air, capable of producing pressure upon the fluid to be raised or made to flow. The operation of this device is obtained preferably by the use of compressed air, but any suitable fluid having properties to produce the pressure could be readily used.

The object of this invention is to provide such simple apparatus as will perform the desired function of elevating a fluid or causing it to flow, against pressure when some motor fluid is used to develop the necessary power, and at the same time have such apparatus constructed so that the entire mechanism can be easily and quickly removed from its casing for the purpose of repairing or cleaning.

A further object of the invention is the elimination of the parts now used in apparatus of this type, especially in the number of casings.

When this device is used in deep well practice, one air compressor would be sufficient to operate several wells at different distances from the source of power. This plan of operation would be very advantageous in mountainous districts. Also in this practice the liquid could be relayed, and the height of lift of any well could be divided into several lifts by placing liquid seals at different intervals according to the height the liquid is to be lifted. By pumping in this manner lower pressure can be used to lift the liquid against a much greater head than low pressure of the actuating fluid could possibly accomplish without the relay method, as the actual head may be exceedingly large in comparison with the actual pressure of the motor fluid.

My device is illustrated in the accompanying drawings, in which:—

Figure 1, is an axial section of my device as applied to well practice, with the upper part of the device, discharge pipe and well casing broken away. Fig. 2, is a similar section of the upper part with part of the

well casing, discharge pipe and actuating fluid pipes broken away. Fig. 3, is an axial section of the sealing of the top of the outside casing with part of the discharge pipe 60 and well casing and actuating fluid pipes broken away. Fig. 4, is a transverse section on the line x, x , of Fig. 1. Fig. 5, is an axial section of my device as constructed for relay pumping. 65

Referring to the drawings, A, is the outside casing of a driven well, and A¹, is a strainer joined to A, in any convenient manner as by means of a coupling, a. An anchor, a¹, comprising a hollow conical 70 wedge, preferably steel, and slit at its top to facilitate expansion, is held in position by roughened, notched or threaded portions of its outside surface, said surface burying itself in the outside casing, A, and forming 75 retention points. A hollow conical wedge, a², is adapted to fit in the hollow conical wedge, a¹, and is capable of forcing said wedge out against the casing, A, when suitable force is applied above; and when so 80 forced causes said conical wedge, a¹, to bury its notches, threads or roughened parts in the inner wall of casing, A.

Discharge pipe, B, and its lining, B¹, preferably brass, which are concentric with casing, A, are held against gravity by means of collar, b, which is threaded or otherwise fixed to B, and rests upon an annular packing ring, b¹, preferably of soft rubber. This packing ring sustains the weight of discharge pipe, B, and the parts which it encloses. Said ring, b¹, has such elasticity that the weight it sustains causes it to seat tightly against both A, and B, and affords a fluid tight joint between the casings, A, 85 and B. Said expanded annular ring rests on the collar, b², which is not threaded to casing, B, but is loosely pierced by the same and rests on the peripheral edge of the conical wedge, a². Collar, b, and sleeve b², have 90 their contiguous surfaces contacting with packing ring, b¹, so shaped as to tend to force the packing firmly against the casings, A, and discharge pipe, B. Collar, b³, is threaded or otherwise fixed to pipe, B, and 95 is contiguous to collar, b², which rests upon it while the device is being lowered into position and before b², contacts with a². The shoe, b⁴, is threaded to the extreme lower end of B, and embraces a conical shaped receptacle into which the extreme lower end 100 of the tube, C, fits. 105

Tube, C, comprises a hollow tube terminating in a projecting annular flange, c^o, whose outside surface is in the shape of a frustum of a cone, adapted to seat tightly in the conical receptacle of shoe, b⁴. Collar, c, rests upon the annular flange, c^o, of tube, C, with which it is concentric. Upon said collar, c, rests cup leather, c¹, which is held tightly in position by collar, c², which fits tightly against a portion of said cup leather and has an annular recess which tends to prevent the vertical portion of said cup leather from falling in toward tube, C, and thus destroy its function. Cup leather, c³, rests upon collar, c², and collar, c⁴, has the same function in combination with cup leather, c³, as collar, c², had in combination with cup leather, c¹.

The extreme upper extremity of tube, C, affords a seat for the ball-valve, c⁶. This ball is loosely confined by a plurality of strips, d, formed in the connecting member, D, and together constitute a cage.

The connecting member, D, is integral, is hollow, annular and interiorly threaded at each end, said ends are of slightly less diameter than the interior of the lining, B¹, and it has interior arches, d³, adapted to suitably limit the reciprocation of the ball, c⁶. The lower end of the connection, D, is threaded to tube, C, and its upper end is attached to C¹, in a similar manner. Its bottom or extreme lower edge fits tightly against the top of collar, c⁴.

The tube, C¹, is threaded at its upper extremity to the inside of the hollow annular lower extremity of the bail, D¹. The outside of the lower portion of D¹, fits slidably in, B¹. Interposed between the threaded ends of tube, C¹, and held rigidly by the pressure transmitted from the end of the connecting member D, and bail, D¹, are cup leathers, c⁷, c⁸, and collars c⁹ and c¹⁰, which are similarly arranged and similar to cup leathers, c¹ and c³, and collars, c² and c⁴, respectively and are functionally identical.

Tube, C¹, at its upper end affords a seat for ball-valve c¹¹, which is retained sufficiently for operation in cage, d², which is similar to the lower cage previously described and is integral with the bail, D¹, of the device; said bail terminating at its upper end in a threaded cylindrical rod, facilitating the fastening of a hook or threaded coupling. The entire device is adapted to be contained in lining, B¹, whose function is to facilitate removal by preventing rusting together of contiguous ferric parts, and said lining extends just a little distance above the top of bail mechanism, D¹. B, and B¹, are cut through by one or more registering slots, b⁷, to afford a passage way for fluid.

The coupling, b⁵, connects, B, with sleeve, b⁶, by means of threads (see Fig. 2). Said

sleeve, b⁶, is loosely pierced by actuating fluid pipes, E, and E¹, and is slidably connected to discharge pipe F, and restricts the amount of sliding of said casing. The sleeve, b⁶, also forms a support for packing ring, f, which is pierced by actuating fluid pipes, E, and E¹, and upon which rests collar, f¹, which is threaded to discharge pipe, F, and fits slidably in casing, A.

The weight of, F, is transmitted to packing ring, f, by collar, f¹, said packing ring resting on sleeve, b⁶. Collar, f¹, and sleeve, b⁶, have their surfaces, which are contiguous to packing ring, f, so shaped as to tend to force said packing ring, f, which is expanded laterally by the weight of discharge pipe F, against the casing, A, and discharge pipe, F, thus forming a fluid tight joint. Actuating fluid pipes, E, and E¹, are threaded in collar, f¹. By means of packing rings, f, and b¹, and contiguous parts, two seals in the casing, A, are formed and it is obvious that the fluid within or without the chamber between the seals can only enter or escape from said chamber through the registering apertures of the pipe lining, B¹.

The casing, A, is closed at the top by a head, a³, attached in any convenient manner as by coupler, a⁵. Said head is pierced by pipes, E, and E¹, around which are formed fluid tight junctions by means of stuffing boxes, e, and e¹. Pipe, E, connects the top surface of the fluid chamber between the seals to the actuating fluid supply and pipe, E¹, also extending to the same chamber and carries a pressure gage (not shown) above.

Head, a³, is bored to fit discharge, F, closely and counter bored to receive the tubular projection of sleeve, a⁴. A plurality of bolts, a⁶, pierce collar, a⁷, and sleeve, a⁴, and are threaded in head, a³. Pipes, E, and E¹, loosely pierce collar, a⁷. Nuts, a⁸, are threaded to bolts, a⁶ and are capable, when tightened, of forcing the tubular projections of sleeve, a⁴, down into the counter bore of the head, a³; said counter bore and said projection forming a stuffing box of which said projection is the gland.

Collar, a⁷, is threaded to discharge pipe, F, and by means of bolts, a⁶, tends to force and hold said pipe down in casing, A, which force transmitted by collars, f¹ and b¹, to annular packing, f and b¹, cause said packings to be compressed and fit tightly against casing, A, and discharge pipe, B, F, thus forming a fluid tight joint.

The operation of this device is as follows:—The fluid to be pumped, naturally flows from the strainer through tube, C, unseats the ball valve, c⁶, and flows out of apertures, b⁷, into the chamber formed by casing, A, and discharge pipe, B, and the seals, b¹, and f. After the said chamber is suitably filled the actuating fluid is allowed to enter pipe, E, and produce pressure upon

the upper surface of the fluid to be pumped. Said fluid then, due to pressure, tends to flow back through aperture or apertures, b^7 , and the ball valve, c^6 , seats automatically 5 due to the pressure above it. After the seating of the said valve, c^6 , the fluid rises through the tube C^1 , unseats valve, c^{11} , and flows toward the exit of the discharge pipe. When the fluid contained in the chamber 10 formed by the casings, A, and the discharge pipe, B, and the upper and lower seals has been forced suitably low in the said chamber by the pressure of the actuating fluid, the said actuating pressure is released through 15 the pipe, E, by connections (not shown) of said pipe. The ball-valve, c^{11} , then seats automatically, due to the pressure of the fluid above it. The fluid in the strainer again begins its natural flow through tube, C, and 20 the operation is repeated. The time allowed the actuating fluid to act would be fixed and would depend upon the weight of the natural flow of the fluid to be pumped, and the difference between the natural pressure 25 and actual head varies in different plants of this type.

What I claim as my invention and desire to secure by Letters Patent of the United States, is:—

30 1. In a compressed-air elevator for liquids, a well-casing, an independent discharge pipe maintained axially therein and extending into the body of water to be lifted; annular packings with an interval 35 between, seated on the periphery of the discharge pipe and expandible radially to seat against the inner wall of the casing to form be-

tween them in said interval a closed annular chamber; an open tube section removably seated in said discharge pipe, and provided with diaphragm valve-seats at opposite sides of a radial opening in the discharge pipe into 40 said annular chamber; lifting check-valves seating on said valve seats, and one or more air pipes extending through the upper packing 45 into the annular chamber.

2. In a compressed-air elevator for liquids, a well casing adapted to be projected into the body of water to be lifted; an independent discharge pipe maintained axially 50 within the casing approximately to the bottom thereof; annular packings arranged with an interval between near the bottom of the discharge pipe and expandible radially to seat against the inner wall of the casing 55 to form between the packings a closed annular chamber; and an open tube section removably seated in said discharge pipe, and provided with diaphragm valve-seats at opposite sides of a radial opening between the 60 interior of the tube section between the valves into said annular chamber; lifting check valves seated on said diaphragm seats; and air-admission and exhaust pipes carried downward in the well casing outside of the 65 discharge pipe into the annular space between the packings.

In testimony whereof I have hereunto set my hand in presence of two subscribing witnesses.
